UNITED STATES PATENT OFFICE.

EUGÈNE SCHNEIDER, OF PARIS, FRANCE, ASSIGNOR TO SCHNEIDER & CIE., OF PARIS, FRANCE, A LIMITED JOINT-STOCK COMPANY OF FRANCE.

AIMING APPARATUS FOR GUNS.

1,361,781.

Specification of Letters Patent.

Patented Dec. 7, 1920.

Application filed June 16, 1919. Serial No. 304,662.

To all whom it may concern:

Be it known that I, EUGÈNE SCHNEIDER, a resident of Paris, in the Republic of France, have invented a new and useful Improvement Aiming Apparatus for Guns, which invention is fully set forth in the following specification.

It is known that any transverse inclination of the trunnions of the gun cradle occurring after a gun has been trained and elevated for firing at a determined target, vitiates the position of the gun barrel both as regards its training and elevation.

In the diagrammatic perspective view shown in Figure 1 of the accompanying drawings $x-x$ designates the axis, assumed to be horizontal, of the trunnions of a gun. $X-X^1$ represents the horizontal plane of the said axis and $Y-Y^1$ represents the vertical plane passing through the axis $R-S$ of the gun barrel aimed at the target, the latter being supposed for the sake of simplicity to be situated in the horizontal plane $X-X^1$. S is the end of the gun barrel.

The gun barrel is elevated above the horizontal plane by an angle α representing the range elevation which corresponds to the distance (range) of the said target.

If in rotating around the point R in the plane of the figure $Y-R-x$, the trunnions should become inclined, their axis will take up a position x^1-x^1 in the said plane; the gun barrel will take up the position $R-S^1$.

The consequence is that its training on the one hand and its elevation on the other are both wrong.

The training is wrong to the extent of the angle $s-R-s^1-\varsigma$ which is inclosed between the original projection $s-R$ and the actual projection s^1-R of the gun barrel upon the horizontal plane $X-X^1$.

The elevation is then equal to the angle θ which is inclosed between the gun barrel $R-S^1$ and its projection $R-s^1$ on the horizontal plane. It is therefore wrong to the extent of the angle $\theta^1=\alpha-\theta$ which are inclosed between the new position of the gun barrel $R-S^1$ and a straight line $R-S^3$ which incloses the angle α with $R-s^1$.

In order to correct the position of the gun barrel as regards elevation, it is in short necessary to elevate it in its plane of rotation through an angle ϵ , that is to say, by operating the elevating mechanism to bring the

gun barrel into the position $R-S^2$ where it will inclose with its projection $R-s^2$ on the horizontal plane $X-X^1$, the angle of elevation α corresponding to the range of the target.

For the purpose of correcting the position of the gun barrel as regards its training, it is necessary to return it into the plane $S-R-s$ by operating the training mechanism.

Now it is necessary to know exactly at all times, by an automatically given indication, the maneuvers to be effected according to the values of the corrections ς and ϵ (or θ^1 projection of ϵ on the vertical plane passing through the axis of the gun barrel), in such a manner as to be able to carry out the necessary operations without having to make any calculation for the purpose.

It is known that for the purpose of determining the amplitude of the maneuver to be performed with the training mechanism, there is usually employed a construction of gun carriage comprising a sighting apparatus movably jointed to one of the trunnions of the gun cradle by a Cardan joint, one of the axes of which is always parallel to the axis of the gun barrel. A mechanism taking its support from the elevating cradle, allows of uprighting the sighting apparatus in such a manner as to bring it back into a vertical plane which is therefore necessarily parallel to the axis of the gun barrel.

When the combination $S-R-x-x$ of the gun barrel and the axle assumes the inclination $S^1-R-x^1-x^1$, the sighting apparatus jointed to the trunnion of the gun cradle will likewise become inclined, and its line of sight will cease to be directed on to the target. To correct the training it is sufficient to uprise the sighting apparatus around its axis of articulation parallel to $R-S^1$, then to operate the training mechanism until the line of sight has been brought back on to the target or sighting register mark, that is to say, until it has returned into the original plane $S-R-s$ or into the plane of indirect sighting. In this manner the gun barrel will be returned into its original vertical plane, and will consequently be suitably aimed.

As a matter of fact, the mere uprise of the sighting apparatus, that is to say, its return into the vertical position, determines

automatically the amplitude of the maneuver to be performed by means of the training mechanism for the purpose of making the correction ς .

5 In gun carriages as hitherto constructed, no apparatus has been provided for furnishing a data for the correction corresponding to ς to be made in the elevation.

In my copending application Serial No. 10 304,660 of even date herewith, there is described an apparatus which gives a practical solution of the two-fold problem of effecting a correction for training and a correction for the elevation. For this purpose the 15 apparatus for reading off the range elevations is arranged in the actual support of the sighting apparatus and this support is jointed in a known manner by a Cardan joint to one of the trunnions of the gun 20 cradle, and is adapted by means of a suitable mechanism to be maintained constantly in a vertical plane parallel to the axis of the gun barrel. In the case of an inclination of the gun trunnions it is sufficient to return 25 the support of the sighting apparatus into the vertical plane by rotation around the axis of the Cardan joint, parallel to the axis of the gun barrel. Owing to this uprighting movement the part of the said apparatus 30 which carries the register mark for reading the range elevations and which is guided in a plane at right angles to the site plane, turns both around the axis parallel to the axis of the gun barrel and around the second 35 axis of the Cardan joint. The result is an angular difference of position between the register mark and the scale division that was situated opposite the latter this angular difference being exactly equal to the angle θ^1 , 40 which is a projection upon the vertical plane passing through the actual axis R—S¹ of the gun barrel of the angle ς through which the gun barrel must be elevated in its plane of rotation for the purpose of correcting the 45 range elevation.

In reality, the improved apparatus described in our aforesaid application for a patent, allows at all times by the mere uprighting of the sighting apparatus, of making not only the correction ς for training, but also the correction for elevation corresponding to the angle θ^1 , that is to say, to the projection on a vertical plane parallel to the axis of the gun, of the angle through 55 which the gun barrel must be raised in its plane of rotation around the axis of the cradle trunnions.

Now it is not always possible to arrange the apparatus for reading the range elevations in the support of the sighting apparatus. More particularly when the known elevating apparatus of the "independent range elevation" type is employed, the apparatus for reading the elevations is necessarily located relatively to the axis of the

gun carriage, on the side opposite to that on which the sighting apparatus is situated.

The present invention has for its object to provide an apparatus combined with an aiming mechanism of the independent elevation type, and furnishing automatically the necessary data for effecting without calculation the corrections of elevation due to the transverse inclinations of the gun carriage wheeled axle. 70

A practical construction of this invention is illustrated by way of example in the accompanying drawings, in which:

Figs. 2 and 2^a are vertical cross sections on the line I—I of Fig. 3 through the axis of 80 the trunnions of the gun cradle of a gun provided with this invention. Fig. 3 shows partly in vertical section and partly in elevation the mechanism comprised between the side plates of the gun carriage. 85

Fig. 3^a is a side elevational view showing the apparatus for reading the range elevation.

In these figures, A is the carriage cradle of a gun, of which a and a^1 are the trunnions. 90 B is the gun carriage proper. C is the elevating cradle of known construction provided with toothed sectors C¹ meshing with pinions D mounted on an axle d journaled in the carriage B. 95

The elevating mechanism comprises for example a nut C² formed in the elevating cradle C, in which there works a screw E carrying a bevel pinion E¹ which latter meshes with a bevel toothed wheel F carried by a shaft f which is journaled in supports fixed to the carriage cradle A. 100

By operating the shaft f , the screw E is moved in the nut C², and the gun cradle is raised or lowered thereby without affecting 105 the elevating cradle C, the sectors C¹ of which mesh with the corresponding pinions D. By actuating the shaft d , the elevating cradle C is caused to revolve, and the latter moves with it the carriage cradle A and the 110 gun barrel.

This known construction comprises means (likewise known) that allow of correcting the training position of the gun barrel when the trunnions of the carriage cradle are inclined. 115

The support G of the sighting apparatus is adapted to pivot around an arm H which is in turn jointed to the left hand trunnion a by means of a hinge h parallel to the axis 120 of the gun barrel. This Cardan joint of the support G allows of returning the latter constantly into a vertical plane parallel to the axis of the gun barrel by rotation around the hinge h irrespectively of the inclination 125 β of the axis of the gun carriage trunnions.

The mechanism for returning the support G into a vertical plane may obviously be of any known type, for instance the type illustrated in Fig. 2, which comprises a slide 130

block G^1 serving as a nut working on a screw G^2 journaled in a prolongation of the elevating cradle C . This slide block has a cylindrical socket g^1 in which is engaged a spherical knob g formed on an extension of the support G .

With a construction of a gun carriage of the known type as hereinbefore described, the apparatus for reading the range elevations 10 is necessarily located on the side opposite that on which the sighting apparatus is situated. Usually this apparatus for reading the range elevations is mounted as hereinbefore stated, for instance, on a shaft, 15 such as the shaft f journaled in the carriage cradle. In all cases, whatever the support of the apparatus for reading the range elevations may be, the range indications furnished by this apparatus, when the axis of 20 the trunnions is inclined, are necessarily incorrect.

According to this invention, the apparatus for reading the range elevations, is movably jointed to the carriage cradle in such 25 a manner as to be capable of being returned at all times in a vertical plane parallel to the axis of the gun barrel. In short, it is connected to the gun barrel (separately and on the side opposite that on which the sighting 30 apparatus is situated), by a connection similar to the one provided for the apparatus for reading the range elevations in my above application for patent where the said apparatus is mounted in the support 35 of the sighting apparatus.

For this purpose it may be mounted on an axle I which is itself movable around a pivot J that is constantly parallel to the axis of the gun barrel and is carried for 40 instance by the right hand trunnion a^1 of the carriage cradle A . The elevation indicating apparatus proper comprises a drum K movable around the axle I , but being always constrained by the movements of the 45 elevating cradle C by reason of an extension K^1 formed with a spherical head K^2 working in a slot guide c projecting from the elevating cradle C , and in a plane at right angles to the plane of longitudinal symmetry of the gun carriage.

The drum K carries a pointer k on the edge of a window K^3 past which there moves a scale marked on the periphery of a range elevation plate L mounted loose on the axle 55 I . The plate L is fixed to a pinion L^1 which meshes with a toothed wheel of large diameter M mounted on a small axle m fixed to the drum K . The toothed wheel M meshes in its turn with a toothed ring n formed on 60 a disk N fixed to the axle I . The ratio between the number of teeth of the toothed ring n and the number of teeth of the pinion L^1 is so chosen as to suitably multiply the ratio of the angular movements between 65 the gun barrel and the range elevation plate.

Normally, that is to say, when the axis of the trunnions $a-a^1$ is horizontal, the axle I will be situated in the prolongation of the axis of the trunnions, and the range elevation plate will be vertical.

70

In such a case, in order to give to the gun barrel the desired inclination corresponding to the range, it is merely necessary to bring the corresponding scale mark on the plate L opposite the register mark k by 75 suitably actuating the shaft f for this purpose. If the target is situated at an elevation above the horizon, that is to say, in other words, if it has a determined angle of site elevation, the left hand gun server 80 gives the site in the known manner, while the right hand gun server gives the range elevation.

85

If the axis of the trunnions $a-a^1$, instead of being horizontal, has an inclination β as indicated in Fig. 1, the indications due to the range, taken from the plate L , are incorrect. But, in order to ascertain the correction for the range elevation, that is to say, the amplitude of the maneuver to 90 be performed with the elevating mechanism in order to bring the gun barrel into the desired position $R-S^2$ (Fig. 1), it will be sufficient to upright the range elevation plate, that is to say, to bring it into the 95 vertical position, which operation will have the effect of producing between the register mark k and the selected scale mark a difference of angular position equal to the angle θ^1 (Fig. 1).

100

If, now, on actuating the elevating mechanism so as to elevate the gun barrel from the position $R-S^1$ (Fig. 1) while keeping the graduated plate L vertical, the angle through which the gun barrel will have yet 105 to pass at each instant in order to arrive at the position $R-S^2$, will always be projected upon the plane of the uprighted graduated plate according to the angle inclosed at that instant between the position of the selected scale mark and the angularly shifted register mark k^1 . In short, the operation for 110 correcting the elevation of the gun barrel, consists in actuating the elevating mechanism in such a manner as to bring the scale mark to k^1 , while the graduated plate L is being kept vertical.

115

The correctness of the foregoing statements can be readily proved by inspecting the diagram shown in Fig. 1. In this diagram it is assumed that the graduated plate L is movably jointed around the straight line $R-S^1$ which is the actual axis of the gun barrel and parallel to the axis J of the Cardan joint.

120

The register mark carrier K is shown diagrammatically reduced to a diametrical axis attached to the plate L (shown in full lines) in such a manner as to rotate compulsorily with it around the axis $R-S^1$ which is none 130

125

other than the axis J of the Cardan joint, while it is capable of rotating at the same time around the second axis I of the said Cardan joint by being guided by the extension K^1 in the slot guide e . The latter extends at right angles to the elevating cradle, and consequently is situated in a vertical plane parallel to the plane $Y-R-x$ when the target is on the horizon (zero site elevation).

In the uprighting movement around $R-S^1$ the scale division corresponding to the range of the target does not move, whereas the register mark k is forced to rotate around the second axis I of the Cardan joint, its tail K^1 being maintained in the slot e .

It is obvious that the lower limb of the register mark holder incloses with the tail K^1 fixed thereto, an angle $90^\circ - \alpha$. When the plate is uprighted, the tail K^1 will have occupied the position indicated in dotted lines, and at right angles to the horizontal plane $X-X^1$, it will always inclose with the lower limb of the register mark holder (come into the position indicated in dotted lines) an angle $90^\circ - \alpha$, and consequently the register mark holder will inclose the angle α with the projection $R-s^1$ of the plate upon the vertical plane. In other words, the register mark k which has come into the position k^1 , has been shifted angularly through an angle θ^1 in relation to the scale division which has remained fixed. It is therefore sufficient to return the scale mark opposite k^1 by means of the elevating mechanism, in order to have elevated the gun barrel through the angle ϵ in its plane of rotation.

In practice, for uprighting the plate around the axle J and maintaining it in the vertical plane passing through the said axle, the axle I may be provided for instance with an arm I^1 forming at its end a cylindrical lodgment for a nut O of corresponding shape fitted in an arm Q fixed to the trunnion a^1 . On actuating the spindle P by means of a knurled knob P^1 , the axle I and with it the drum K is shifted. In this manner the said drum can be brought back into the vertical plane parallel to the axis of the gun barrel. In view of the fact that in this uprighting movement the axle I revolves around the joint J in a plane at right angles to the axis of the gun barrel, while the drum K , held by the knob K^2 in the slide e , revolves at the same time around the axle I , the result is, as has been above stated, to produce a relative displacement between the drum K and the toothed ring n fixed to the said axle I . In this movement, the register mark k is shifted through the angle θ^1 relatively to the scale division which was situated opposite it.

If this angular shifting is corrected by

operating the shaft f in such a manner as to bring the selected division of the scale of range elevations opposite the register mark k , while actuating the knob P^1 in such a manner as to keep the plate vertical, by observing the bubble of the spirit level T , the gun barrel will be made to pass through the angle in its plane of rotation.

At each instant, the angle which has still to be passed through, is indicated on the plate of range elevations (that is kept vertical) by the angular distance between the selected scale division and the register mark k .

It is quite obvious that the joint J parallel to the axis of the gun barrel, instead of being carried directly by the trunnions a^1 of the cradle, may be carried by any suitable support which will be in constant connection with the movements of the cradle, for instance by means of a parallel motion.

What I claim is:

1. In combination with a gun carriage cradle adapted to be elevated and depressed with the elevating cradle and independently in relation with the latter, a sighting apparatus having a Cardan joint connection with the carriage cradle on one side thereof and adapted during uprighting to automatically correct for training due to transverse inclination of the trunnions, and a range elevation registering device mounted on the opposite side of said carriage cradle having a Cardan joint connection therewith and adapted during uprighting to correct for elevation due to transverse inclination of the trunnions and adapted to register sight elevations as indicated on said sighting apparatus.

2. In combination with a gun carriage cradle adapted to be elevated and depressed with the elevating cradle and independently with relation to the latter, a sighting apparatus having a Cardan joint connection with the gun carriage cradle on one side of the latter, one axis of the joint being parallel with the gun axis, means on the elevating cradle for uprighting the sighting apparatus when the cradle trunnions are in-lined, range elevation indicating apparatus mounted on the opposite side of said cradle comprising:—a Cardan joint having one axis parallel with the gun axis, a register mark holder revolubly mounted on the companion axis, a graduated disk adapted to register with the holder and having gear connections with said latter axis and with said holder, means for uprighting said holder, and means carried by the elevating cradle for guiding the uprighting movement of said holder.

3. In combination with a gun carriage cradle adapted to be elevated and depressed with the elevating cradle and independently in relation with the latter, a sighting appa-

49

1,361,781

5

ratus having a Cardan joint connection with the gun carriage cradle on one side of the latter, one axis of the joint being parallel with the gun axis, means on the elevating 5 cradle for uprighting said apparatus when the cradle trunnions are inclined, a range elevation indicating apparatus mounted on the opposite side of said carriage cradle comprising:—a register mark holder and a re- 10 voluble disk having graduations adapted to register with that of the holder, said holder having a Cardan joint connection with said gun carriage cradle, the axis of one joint

being parallel with the gun axis, and a loose guiding connection with said elevat- 15 ing cradle, means for uprighting said holder carried by the carriage cradle, said disk having operating connections with one axis of said joint and with said holder.

In testimony whereof I have signed this 20 specification.

EUGÈNE SCHNEIDER.
